UNITED STATES PATENT OFFICE.

KARL V. NILSON AND JOHN NELSON, OF CHICAGO, ILLINOIS, ASSIGNEES TO MARQUETTE TOOL & MANUFACTURING CO., OF CHICAGO, ILLINOIS, A CORPORATION OF ILLINOIS.

SPRING DIE CUSHION.

Application filed October 15, 1923. Serial No. 668,506.

To all whom it may concern:

Be it known that we, KARL V. NILSON and JOHN NELSON, citizens of the United States, residing at Chicago, in the county of Cook and State of Illinois, have invented certain new and useful Improvements in Spring Die Cushions, of which the following is a specification.

This invention relates to improvements in spring die cushions particularly adapted, though not necessarily limited in its use, in connection with the type of machine generally known as punch presses and to the cushion for yieldingly sustaining the draw ring.

Heretofore in cushions of this character in which springs are employed for cushioning purposes, the pressure or resistance of the spring is generally increased as the stroke progresses.

It sometimes happens that it is desired to vary this pressure so as to decrease or increase toward the end of the stroke, and at other times it is desirable that there shall

be a substantially unvarying pressure of the cushion throughout the length of the stroke.

With the spring cushions as now employed such a change is not possible.

It is one of the objects of the present invention to provide improved mechanism of a simple and compact construction which may be readily adjusted in accordance with the requirements of the work and material being operated upon in the machine.

A further object is to provide an improved cushion of this character which may be readily installed.

To the attainment of these ends and the accomplishment of other new and useful objects as will appear, the invention consists in the features of novelty in substantially the construction, combination and arrangement of the several parts hereinafter more fully described and claimed and shown in the accompanying drawings illustrating this invention and in which

Figure 1 is a vertical longitudinal sectional view of a portion of a press having a cushion constructed in accordance with the principles of this invention applied thereto, and showing the parts in one position.

Figure 2 is a detail vertical sectional view of the cushion showing the parts in another position.

Figure 3 is a horizontal sectional view as taken on line 3—3, Figure 1.

Figure 4 is a detail perspective view of one of the levers, forming a part of the cushion.

Referring more particularly to the drawings the numeral 10 designates generally a bolster plate of a punch press, having a male die member 11 secured thereto and co-operating with the male die member 11 is a female die member 12, the latter being connected to a movable part of the press to be reciprocated in the ordinary and well known manner.

Encompassing the die member 11 is a draw ring 13, supported by means of the usual pins 14 which engage the bottom of the member 13 and these pins 14 pass loosely through the bolster plate 10 to engage and rest upon a pin plate 15, the draw ring 13 co-operating with the die member 12 to grip the work 16. All of the above referred to parts are of the ordinary and well known construction.

The pin plate 15 is supported by means of a spring cushion, which in the present form of the invention consists of an anchor bolt 17, one end of which is detachably secured to the bolster plate 10 in any desired or suitable manner, such as by means of a threaded extremity 18 engaging a threaded socket in the bolster plate 10. This anchor bolt 17 forms a support for the cushion and may be of any desired length, the free extremity thereof being threaded to receive a nut or collar 19.

Loosely encompassing the bolt 17 is a tubular member 20 which is provided with screw threads 21 adjacent its lower extremity. The end of the member 20 rests upon the nut or collar 19 while the end 22 thereof may either terminate short of the pin plate 15 or is adapted to project into a suitable aperture 23 in the pin plate so as not to interfere with the longitudinal adjustment of the element 20 upon the element 17. This adjustment is accomplished through the medium of the nut or collar 19 being adjusted upon the threaded extremity of the element 17.

A nut or collar 24 is threaded upon the threads 21 on the end of the element 20. Encompassing the element 20 is an elastic element 25 preferably in the form of a coil

spring, one end of which spring rests upon the collar 24 and upon the other end of the spring 25 a collar 26 rests, the latter loosely surrounding the element 20.

5 Interposed between the collar 26 and the pin plate 15 are cam formations preferably in the form of levers, each lever being provided with arms 27—28, the arms of each lever being preferably arranged at angles 10 to each other so that the levers of each co-operating pair may be pivotally connected as at 29. These elements are preferably arranged in pairs and the points of pivotal support of the respective pairs of levers are 15 connected with the tubular element 20 so that when the tubular element 20 is adjusted lengthwise of the element 17 the cam formations will be bodily adjusted therewith.

The extremities of the arms 27 engage 20 the lower face of the pin plate 15 while the extremities of the arms 28 engage the adjacent face of the collar 26. If desired and in order to reduce friction between the contacting points of the arms 27 and the pin plate 15, anti-friction rollers 30 may be provided and similar anti-friction rollers 31 may be connected with the ends of the arms 28 to engage the collar 26.

30 The arms 27—28 may be of any desired length and the cam elements are adapted to be moved about their pivots 29 so as to vary respectively the points of contact between the rollers 30 and the pin plate 15 and the rollers 31 and the collar 26.

35 By varying these points of contact it will be manifest that the leverage of the cam formations upon the collar 26 may be varied by varying the points of contact of the respective portions of the cam elements with 40 the elements 15 and 26. This variation in leverage which occurs by the adjustment of the cam elements will control the action of the spring 25.

In Figure 1 the cam formations are so positioned with respect to the pin plate 15 and collar 26 that upon the operation or depression of the draw ring 13 under the influence of the die member 12, the spring or elastic element 25 will be compressed in such a 50 manner that as the draw ring is depressed the pressure on the spring 25 will increase, as the spring is compressed, toward the end of the stroke.

55 In order therefore to vary this operation upon the spring and to cause the spring or pressure to decrease upon the descent of the draw ring 13, the cam formations should be adjusted to the position shown in Figure 2, that is to say the ends of the arms 28 should 60 be separated or moved further away from the line of the center of the pivot of the cam formations, while the ends of the arms 27 should be moved toward such centers from the position shown in Figure 1, until the 65 parts assume the position as shown in Fig-

ure 2. In this position of the parts and when the pin plate 15 is depressed the spring 25 will also be compressed but in such a manner that the pressure on the spring or elastic element will decrease toward the end 70 of the stroke.

Obviously when it is desired that there shall be a substantially unvarying pressure of the spring 25 throughout the limit of the stroke, the cam formations may be adjusted 75 so as to position the ends thereof respectively with relation to the pin plate 15 and the collar 26, to accomplish this result.

While the cam formations have been herein shown and described as consisting of a substantially bell crank lever formation it is to be understood that they may be of any desired configuration suitable for the purpose. It will also be understood that where-as the elastic element 25 has been herein 85 shown and described as a spring, the same may be constructed of any other resilient or elastic substance.

To accomplish the adjustment of the cam formations it is only necessary to adjust the 90 collar 19 upon the element 17, thereby raising or lowering the pivot point 29 with respect to the bolster plate 10, and to vary the initial stress of the elastic element 25 against the collar 26, the nut or collar 24 should be 95 adjusted upon the element 20. During the adjustment of the nut or collar 19 on the element 17 to bodily raise or lower the cam formations, it is manifest that the elastic element will exert its stress upon the cam 100 formations through the medium of the collar 26 and this will cause the cam formations to assume the proper positions or "follow" during the adjustment of the element 20.

105 Obviously the end of the element 20 adjacent the pivot 29 of the cam formations is so shaped or constructed that the end of the element 20 will not interfere with the movement of the cam elements about the 110 pivot 29.

The term lever will be employed through the claims to designate the cam formation but it is to be understood that this is not to be considered as a term of limitation as a 115 lever or any cam formation suitable for the purpose may be employed.

Obviously, many changes in the details of construction and in the combination and arrangement of the several parts may be 120 made, within the scope of the claims, without departing from the spirit of this invention.

What is claimed as new is:—

1. A spring die cushion embodying a 125 movable member, a spring resisting movement of said member, levers pivotally mounted intermediate their ends and disposed between the said spring and movable member and operating upon both, the move- 130

ment of the said member in one direction operating to move the levers about their pivots and against the stress of the spring, means for adjusting the normal relative position 5 of the levers with respect to each other to vary the normal relative position of the said member and spring, and means for bodily adjusting the levers.

2. A spring die cushion embodying a movable member, levers pivotally mounted intermediate their ends, a movable element spaced from the said member, an adjustable support, levers pivotally mounted intermediate their ends upon the support and disposed 15 between the said movable member and element, elastic means for opposing the movement of the said levers about their pivots, and means for adjusting the said support for varying the normal position of 20 the said pivot of the levers with relation to the said movable member.

3. A spring die cushion embodying spaced movable members, levers pivotally mounted intermediate their ends, the respective ends 25 of the levers having engagement with both the said members, one of the members tending to move the levers about their pivots to move the other of said members, an elastic element resisting the last said movement of 30 the said levers about their pivots, and means for varying the respective points of contact of the ends of the said levers with the said members.

4. A spring die cushion embodying spaced 35 movable members, levers pivotally mounted intermediate their ends, the respective ends of the levers having engagement with both the said members, one of the members tending to move the levers about their pivots to move 40 the other of said members, an elastic element resisting the last said movement of the said levers about their pivots, and means for shifting at will the position of the pivots of the levers with relation to one of the said 45 members.

5. A spring die cushion embodying spaced movable members, levers pivotally mounted intermediate their ends, the respective ends 50 of the levers having engagement with both the said members, one of the members tending to move the levers about their pivots to move the other of said members, an elastic element resisting the last said movement of 55 the said levers about their pivots, an adjustable support to which the said levers are pivoted, and means for adjusting the said support at will.

6. A spring die cushion embodying spaced 60 movable members, levers pivotally mounted intermediate their ends, the respective ends of the levers having engagement with both the said members, one of the members tending to move the levers about their pivots to move 65 the other of said members, an elastic element resisting the last said movement of

the said levers about their pivots, means for varying the respective points of contact of the ends of the said levers with the said members, and means for varying at will the normal tension of the said elastic element. 70

7. A spring die cushion embodying a movable member, a stationary element, a support adjustably mounted upon the said element, a collar sleeved upon the support, an elastic element resisting the movement of 75 the collar in one direction upon the support, levers pivoted intermediate their ends upon the support, said levers being disposed between the said movable member and the said element, the respective ends of the levers 80 having engagement with the said movable member and element, the action of the said movable member upon the levers tending to move the levers about their pivots to move the said collar against the stress of the said 85 elastic element, and means for varying at will the normal tension of the said elastic element.

8. A spring die cushion embodying a movable member, a stationary element, a support adjustably mounted upon the said element, a collar sleeved upon the support, an elastic element resisting the movement of 90 the collar in one direction upon the support, levers pivoted intermediate their ends 95 upon the support, said levers being disposed between the said movable member and the said element, the respective ends of the levers having engagement with the said movable member and element, the action of the 100 said movable member upon the levers tending to move the levers about their pivots to move the said collar against the stress of the said elastic element, and means for adjusting the said support at will to vary the 105 position of the pivot of the said levers with relation to the said movable member.

9. A spring die cushion embodying a movable member, a stationary element, a support adjustably mounted upon the said element, a collar sleeved upon the support, an elastic element resisting the movement of 110 the collar in one direction upon the support, levers pivoted intermediate their ends upon the support, said levers being disposed between the said movable member and the said element, the respective ends of the levers 115 having engagement with the said movable member and element, the action of the said movable member upon the levers tending to move the levers about their pivots to move the said collar against the stress of the said elastic element, means for adjusting the said support at will to vary the position of the 120 pivot of the said levers with relation to the said movable member, and means for varying at will the normal tension of the said elastic element.

10. A spring die cushion embodying a 125 tubular member, an anchor bolt upon which 130

the member is sleeved, a collar adjustably connected with the bolt and operable to move the tubular member longitudinally of the bolt, a second collar loosely sleeved upon 15
5 the said member, a collar adjustably connected to the tubular member, an elastic element encompassing the said member with its ends in operative engagement with the last two recited collars, a movable member
10 spaced above the first recited collar, and levers pivotally mounted intermediate their

ends upon the said tubular member and bodily adjustable therewith, the respective ends of the levers having contact with the said second collar and the said movable member.

In testimony whereof we have signed our names to this specification, on this 10th day of October, A. D. 1923.

KARL V. NILSON.
JOHN NELSON.
